UNITED STATES PATENT OFFICE.

EDWARD J. BRANDT, OF WATERTOWN, WISCONSIN, ASSIGNOR TO BRANDT AUTOMATIC CASHIER COMPANY, OF WATERTOWN, WISCONSIN.

RESETTING MECHANISM.

Original application filed March 21, 1918, Serial No. 223,786. Divided and this application filed May 8, 1919. Serial No. 294,400.

To all whom it may concern:

Be it known that I, EDWARD J. BRANDT, a citizen of the United States, residing at Watertown, in the county of Jefferson and State of Wisconsin, have invented certain new and useful Improvements in Resetting Mechanism, of which the following is a specification, reference being had therein to the accompanying drawing.

10 The invention relates to improvements in a resetting mechanism for registers, calculators or like devices and is a divisional application of my co-pending application Serial No. 223,786, filed March 21, 1918.

15 It is an object of the invention to provide a simple and efficient means for resetting a plurality of indicators to a zero or normal position.

20 A further object of the invention is to provide a mechanism of this character comprising friction members adapted to bear against indicators and keyed to the shaft upon which the indicators are loosely mounted, so that upon a rotation of the shaft the 25 indicators will be correspondingly moved by the friction members to a zero or normal position where they are held by a suitable stop.

More specifically the invention comprises 30 a resilient washer having separated resilient arms adapted to impinge upon an indicator to turn the indicator upon a rotation of the shaft upon which the spring washers are mounted to reset the same to a zero position, 35 it, of course, being understood that there are a plurality of indicators and a spring washer for each indicator so that as one indicator is positively stopped upon its reaching a zero position the arms of the spring washer ride over its face until all of the indicators have 40 been lined up in a zero position. In the preferred embodiment of the invention the spring washers are normally out of contact with the indicators and move into driving relation therewith upon an endwise movement of the shaft, but if found desirable the arms of the spring washers can at all times be in frictional contact with the indicators so that 45 an endwise movement of the shaft is not necessary in order to reset the indicators.

In the accompanying drawings I have illustrated the preferred embodiment of the invention, but many changes may be made in construction and arrangement of parts

without departing from the spirit of the invention.

In the drawings:

Fig. 1 is a longitudinal sectional view through the machine.

Fig. 2 is a front view with a portion of the 60 casing broken away to show the interior structure.

Fig. 3 is an enlarged vertical section of the forward portion of the machine.

Fig. 4 is a transverse vertical section 65 through the casing to show the front of the operating mechanism.

Fig. 5 is a detail fragmentary sectional view through the upper rollers for the indicating bands or strips and immediately associated parts.

Fig. 6 is a fragmentary longitudinal vertical section of the carrying mechanism disposed between each pair of indicating bands or strips.

Referring now more particularly to the drawings wherein like reference characters indicate corresponding parts, the letter A represents the bottom or base of the machine upon which a cover or casing portion B, 80 usually formed of metal is mounted and secured through the medium of the flanges C. The casing is provided with a shelf or ledge D, slotted as at E for the passage therethrough of a plurality of keys F the same 85 being of any number desired and of convenient arrangement.

Below the shelf or ledge are a series of pivoted plates G connected to the operating rods H and adapted to be shifted by engagement with the fingers or cams I carried by the movable bars J, one bar, of course, being connected with each key, and as each operating rod and its associated indicating mechanism operates in the same manner the 90 description of one operating rod and its mechanism will suffice for all. Each operating rod for the purpose of illustrating a means for operating the register mechanism is shown as carrying at its forward end a 95 pawl K held upwardly with reference to the bottom or base of the machine by a spring L. The pawl K is positioned and held in position by the spring L to engage a rotatable ratchet M fixed to rotate with the roller N, 100 all of the rollers and ratchets of the entire mechanism being carried by a common shaft N extending transversely through the ma-

chine and mounted for rotation in the opposite side walls of the casing B. The ratchet is prevented from reverse rotation by a dog O pivoted in any convenient manner, it being here observed that the rollers always rotate in the same direction, to-wit, the direction indicated by the arrow in Figure 1, whether in a calculating process, or during a resetting of the indicators.

10 Peripherally of the roller M, which may be termed a driving roller, projects a multitude of pins or teeth o adapted to engage complementary apertures p in the counting and indicating band P, said band or strip 15 being of continuous or endless character and being vertically positioned within the machine to pass around a similar idler roller Q loose upon a transverse shaft q extending across the machine and supported at one 20 end by one of the side walls of the casing as at q² and at its other end upon an interior support q³ fixed to the casing in any convenient manner. The band P and the other bands throughout the machine carry the numbers to be indicated from one to any total desired and within the capacity of the band, for example, 99, it being my intention to use a pair of bands in association with each 25 key which could indicate a total of 9,999 30 which would obviously render the same universal in its use and serve all ordinary purposes although of course any number of associated bands of each unit could be added should the particular occasion therefor 35 arise.

The interfitting toothed and apertured portions of the roller M and the indicating band P is for the purpose of positively driving the band through its course of travel 40 upon the operation of its rod H to successively present the numbers on the face of the band opposite a sight opening B' at the forward top of the casing B to be readily observed by the operator of the machine for 45 ascertaining his totals.

Any convenient means may be employed for preventing over-running of the ratchet L and its roller M, as well as the associated parts receiving motion from the ratchet. 50 There is provided on the lower face of the pawl K a bevel stop R adapted to engage and ride upwardly on the lug r on the face of the machine, the relative positions of the stop and lug being such that they come into 55 engagement at about the end of a full stroke of the pawl to force the pawl upwardly into crowding relation to the ratchet, that is to occupy the space between the teeth of the ratchet thus preventing the 60 ratchet from any possible over-throw after each successive rotation.

To carry over from the band P to the adjacent band of a pair or unit represented by the character P', I form on the band P 65 a pin r' which when the band reaches its

99 indicating position will contact with the free end of the pivoted lever S carrying a horizontally disposed pawl S' pivoted thereto and held upwardly by a spring s' bridging the lower end of the lever and the 70 pawl as shown in Figure 6. The lower end of the lever S and its pawl S' are normally held in outward inactive position by the spring s'', but in effective or operating position the nose of the pawl engages a ratchet T fixed to rotate with the driving roller T' having a toothed and apertured engagement with the band P' similar to the engagement between the rolled M and its band P. When the band P engages in its movement the upper free end of the lever S the lower end is forced inwardly and the pawl S' carried thereby engages the ratchet T, rotates its roller T' and correspondingly rotates the band P' to carry over into "one" 80 which added to the zeroes simultaneously presented by the band P will afford a combined indication of one hundred. A dog t³ prevents reverse rotation of the secondary ratchet and its associated parts. While I have shown and described a special form of carry over mechanism it will be distinctly understood that any suitable or well known construction for accomplishing this purpose 85 can be used and the present invention is not limited to any specific indicator actuating mechanism or carry over device but the present construction is merely described for the purpose of illustrating a means for operating the indicators and for carrying over 90 from one indicator to the other.

The indicators are operated successively upon the manipulation of the keys, and when the work of the machine has been completed and it is desired to restore the indicating bands P and P' to a normal or zero position I utilize the following instrumentalities which constitute the subject matter of this application, which is a division of my co-pending application Serial No. 223,- 786. 105

The band P' is provided with a pin p^a corresponding with the pin r' on the band P which has been described as operating the carry over lever S, but when it is intended to reset the indicators, hooks U are thrown into an underlying position with reference to the pins to engage the latter and hold all the bands in aligned zero positions. The hooks U are carried by a rod u secured in arms u' sleeved as at u² upon the shaft q and held against longitudinal movement on said shaft. The shaft is normally held in extreme right position with its handle W in a corresponding position, see Figure 2, by a spring w bearing against the inner end 110 of the shaft q and supported by the portion J³. This spring also frictionally holds the shaft in a normal position against rotation when the idlers Q are revolved thereon. 115 120 125 130

When it is desired to thrust the hooks U below the pins r' and p' it is simply necessary to engage the handle and force the shaft inwardly against the resistance of the 5 spring w which correspondingly carries the arms u' to the left and places the hooks U directly in the path of movement of the pins and constitute a stop therefor.

Mounted upon the shaft to the left of 10 each indicator is a friction clutch Y adapted to yield and bear against the adjacent faces of the idler rollers Q which are dished for this purpose as at Y' Figure 5. This engagement takes place when the shaft is 15 moved against the tension of the spring w and the frictional engagement between the members Y and idler rollers Q temporarily converts said rollers into driving wheels and the rotation of the shaft by its 20 handle w in the direction of the arrow will cause all of the counting and indicating bands P and P' to move around until each of their respective stops r' and p' engage the corresponding hooks U, thus restoring the 25 entire machine to normal or zero position. Of course, as soon as any one of the bands is positively stopped in its movement by the pin and hook engagement the roller of that particular band will remain stationary permitting 30 the resilient member Y to slip or ride over its face. The members Y are keyed to the shaft as indicated at y' and stops y^2 on the shaft serve to limit the end-wise movement of the otherwise freely 35 mounted rollers Q so as to permit the resilient members Y to impinge upon the rollers when the shaft is shifted and the indicators are to be reset.

Having thus described the invention, what

40 I claim is:

1. In a machine of the character described, a series of indicators, and means for resetting said indicators including rotatable frictional devices adapted to be moved into 45 driving relation with said indicators to enable the rotation thereof upon the rotation of said friction devices.

2. In a machine of the character described, a series of rotatable indicating elements including rotating rollers, means for normally actuating said indicating elements, and other means for setting said elements including rotatable friction devices adapted to be moved axially of the rollers in contact 55 therewith to enable the rotation of the rollers with said friction devices.

3. In a machine of the character described, a series of rotatable indicator elements including rotating rollers, means for normally actuating said indicator elements, and other means for setting said elements including rotatable friction devices adapted to be moved axially of the rollers into contact therewith to enable rotation of the 60 rollers with said friction devices, said friction

devices including radially disposed spring arms adapted to yieldably engage the face of the rollers when forced into abutting relation therewith.

4. In a machine of the character described, a series of rotatable indicator elements including rotating rollers, means for normally actuating said indicator elements, and other means for setting said elements including rotatable friction devices adapted to be moved axially of the rollers into contact therewith to enable rotation of the rollers with said friction devices, said friction devices including radially disposed spring arms adapted to yieldably engage the face of the rollers when forced into abutting relation therewith, and the said faces of the rollers being dished to enable conformity of the spring arms therewith. 70 75 80

5. In a machine of the character described, rotatable indicating means including a series of rollers, a shaft on which the rollers are freely mounted, means for normally actuating said indicating means, and other means for setting said indicating means comprising spring friction elements carried by said shaft and capable of longitudinal movement with the shaft to impinge the same against the face of the rollers to cause rotation of the rollers therewith. 85 90 95

6. In a machine of the character described, rotatable indicating means including a series of rollers, a shaft on which the rollers are freely mounted, means for normally actuating said indicating means, other means for setting said indicating means comprising spring friction elements carried by said shaft capable of longitudinal movement with the shaft to impinge the same against the face of the rollers to cause rotation of the rollers therewith, in combination with means normally causing the shaft and said spring friction elements to be removed from frictional connection with the rollers. 100 105

7. In a machine of the character described, an indicator band, oppositely disposed rollers around which the band passes, means for positively driving one of said rollers and with it the indicator band, and other means for setting the indicator band including a stop carried by the band, a co-operating shiftable stop adapted to be thrown into the path of movement of the said first mentioned stop, and means adapted to frictionally engage one of the rollers and 110 to be rotated to shift the band until the stops engage. 115 120

8. In a machine of the character described, an indicator band, oppositely disposed rollers around which the band passes, means for positively driving one of said rollers and with it the indicator band, and other means for setting the indicator band including a stop carried by the band, a co-operating shiftable stop adapted to be 125 130

thrown into the path of movement of the said first mentioned stop, means adapted to frictionally engage one of the rollers and to be rotated to shift the band, and a similar indicator band with its rollers and its normal operating and setting means, the friction devices being adapted to permit yielding against further rotation of one band when its stops are engaged to permit continued rotation of the other band until its stops are engaged.

9. In a machine of the character described, a series of rotatable indicators, a shaft, means mounted to turn with the shaft for resetting said indicators comprising friction devices having separated resilient arms adapted to impinge upon the indicators to rotate said indicators upon a rotation of the shaft, said friction devices being normally out of contact with the indicators and adapted to be placed in driving relation therewith upon an endwise movement of the shaft.

10. A machine of the character described comprising vertically spaced shafts, rollers secured to one shaft, rollers loosely mounted on the other shaft, bands encircling the rollers of the two shafts, means for positively driving the rollers secured to the one shaft, friction members carried by that shaft having the rollers loosely mounted thereon, means for longitudinally moving the last mentioned shaft to bring the friction members into engagement with the loosely mounted rollers, and means for rotating the shaft.

11. A machine of the character described comprising vertically spaced shafts, rollers secured to one shaft, rollers loosely mounted on the other shaft, bands encircling the rollers of the two shafts, means for positively driving the rollers secured to the one shaft, friction members carried by that shaft having the rollers loosely mounted thereon, means for longitudinally moving the last mentioned shaft to bring the friction members into engagement with the loosely mounted rollers, a spring engaging one end of the shaft for normally holding the friction members out of contact with the rollers, and means for rotating the shaft.

12. A machine of the character described comprising vertically spaced shafts, rollers secured to one shaft, rollers loosely mounted on the other shaft, bands encircling the rollers of the two shafts, means for positively driving the rollers secured to the one shaft, friction members carried by that shaft hav-

ing the rollers loosely mounted thereon, means for longitudinally moving the last mentioned shaft to bring the friction members into engagement with the loosely mounted rollers, means for rotating the shaft, a spring engaging one end of the shaft for normally holding the friction members out of contact with the rollers, and means for engaging the belts to hold them so that the rollers will be held against the action of the friction members.

13. A machine of the character described comprising vertically spaced shafts, rollers secured to one shaft, rollers loosely mounted on the other shaft, bands encircling the rollers of the two shafts, means for positively driving the rollers secured to the one shaft, friction members carried by that shaft having the rollers loosely mounted thereon, means for longitudinally moving the last mentioned shaft to bring the friction members into engagement with the loosely mounted rollers, a spring engaging one end of the shaft for normally holding the friction members out of contact with the rollers, means for rotating the shaft, pins secured to the bands, and means adapted to engage the pins so that the rollers will be held against the action of the friction members.

14. In a machine of the character described, a series of indicators, frictional devices normally out of engagement with the indicator, and means for operating said frictional devices to engage them with the indicators for resetting the indicators.

15. In a machine of the character described, a series of indicators, a frictional device adapted to engage each indicator but normally out of engagement therewith, means for simultaneously engaging the frictional devices with the series of indicators, and means for rotating the frictional devices to reset the indicators.

16. In a machine of the character described, a series of indicators, means for operating said indicators, frictional devices adapted to engage the indicators but normally out of engagement therewith, and means for operating the frictional devices, independent of the operating means for the indicators, to reset the indicators.

In testimony whereof I hereunto affix my signature in the presence of two witnesses.

EDWARD J. BRANDT.
